ATTORNEY

UNITED STATES PATENT OFFICE.

HARRY HEFFNER, OF CLEVELAND, OHIO.

SLED.

Application filed May 18, 1923. Serial No. 639,979.

To all whom it may concern:

Be it known that I, HARRY HEFFNER, a citizen of the United States, residing at Cleveland, in the county of Cuyahoga and State of Ohio, have invented new and useful Improvements in Sleds, of which the following is a specification.

My present invention has reference to an amusement device for children, the same being in the nature of a sled which has fixedly attached to the seat board thereof a pair of rear runners and which is provided below and adjacent to the front of the seat board with a single runner having a staff or handle journaled in bearings of a particular and peculiar construction secured to both the upper and lower faces of the board, said handle having at its upper end an operating wheel, while secured to the under-face of the said board are lateral extensions that provide rests for the feet of the user.

A further object is to produce a sled in which a pair of rear runners are fixed to the seat board by a metal frame of a particular and peculiar construction, said runners being formed of wood but being shod with metal, and the said metal being substantially V-shaped in cross section, while arranged below the foot board and centrally with respect to the rear runners there is a single runner of wood shod in a manner similar to that of the rear runners, a handle or staff passing through the board and being connected to bearings of a particular and peculiar construction upon both the top and bottom of the said board to hold the same at a desired angle, said handle being removably secured to the front runner, the device being provided with rests for the feet of the user as well as with means for locking the handle or shaft from turning as when the sled is to be hitched to a similar vehicle.

To the attainment of the foregoing and other objects which will present themselves as the nature of the invention is better understood, reference is to be had to the drawings which accompany and which form part of this application.

In the drawings:—

Figure 1 is a side elevation of a sled in accordance with this invention.

Figure 2 is a bottom plan view thereof.

Figure 3 is a top plan view thereof.

Figure 4 is a sectional view on the line 4—4 of Figure 3.

Figure 5 is a sectional view on the line 5—5 of Figure 4.

Figures 6 and 7 are perspective views of the castings providing bearings for the handle of the front runner.

Figures 8 and 9 are similar views of the castings providing the upper bearings for the said shaft or handle.

The body board of the improvement is indicated by the numeral 1 and is formed of a piece of suitable stout wood. The board has its sides rounded inwardly toward its forward end so that the rear of the board will provide a convenient seat for the user. Secured to the under face of the body, at the seat portion thereof there are rightangularly arranged metal plates 2 and 3 respectively. The transversely disposed plates 2 have their ends bent at downward and outward angles, providing arms 4, the ends of the said arms being offset and let in transverse notches in the upper edges of the rear runners 5. The rear runners are connected together by spaced bars 6. The longitudinal plate 3 has its ends bent at downward and outward angles to provide a rear arm 7 and a forward arm 8. Both of these arms have their ends bent angularly in opposite directions and let in notches and secured to the brace members 6. The forward arm 8 is continued at an upward and outward angle from its connection with the forward brace 6, having an angle end which underlies and which is secured to the under face of the board 1, by means 9. The rear runners and the spacing bars therefor are constructed of wood, but the said runners are shod with metal. The shoes 10 have inner flat faces, but their outer faces are thickest at the center thereof and gradually decrease in thickness to feather edges so that the said shoes are substantially V-shaped in cross section.

This is an important feature of the invention as the pointed central portions of the runners engaging the icy ground surface will prevent the lateral movement or skidding of the sled.

The rear runners have their outer lower corners rounded and their inner corners arranged at an upward inclination, as clearly disclosed by the drawings.

The front runner, which is disposed centrally between the rear runners is indicated by the numeral 11. This runner has its lower edge struck at a curvature from its

front to its rear and both its front and rear are rounded. The front runner has a metal shoe 12 of a similar construction to the shoes 10. The front runner is removably secured 5 to the lower and bifurcated end of a steering post 13. The securing means 14 between the post and runner are preferably in the nature of removable elements. The post may be and is preferably formed of wood. 10 On its under face and surrounding a central opening in the body at the forward end thereof there is secured a casting 15. The casting comprises a body member which is round in plan having laterally extending 15 ears through which the securing means pass that sustain the same on the board 1. The casting is provided with an outstanding peripheral flange, and the body of the casting gradually decreases in thickness from its 20 inner to its outer end so that the said body is disposed at an angle with respect to the plane of the board 1. Received in the flange of the casting 15 there is a disk 16. This disk has a central opening that registers 25 with an opening in the body of the casting 15, and in a line with said opening is provided with opposed cross sectionally rounded lugs 17. The post 13 passes through the openings in the disk and in the casting, and 30 is secured to the disk by removable means 18 that pass through the lugs 17 of the said disk.

On its upper face, and disposed opposite the casting 15 there is secured to the board 1 35 a second casting 19 of a construction similar to the casting 17 and which has its body portion gradually decreasing in thickness from its outer to its inner end. In the flanged periphery 20 of the casting 19 there is a disk 40 21, the said disk having a central opening that registers with a similar opening in the body of the casting 19. In a line with the opposed walls provided by the opening in the disk there are outstanding lugs 22. The 45 post passes through the openings in the casting 19 and disk 21 and is connected to the disk by removable means 23 that pass through the lugs 22. The post has on its upper end a hand wheel 24. Between the 50 disks and castings there may be anti-frictional balls 25, and also one or both of the disks may be and preferably is formed with an upwardly extending finger 26 to be received in an arcuate slot 27 in one or both 55 of the castings whereby to limit the turning of the post with its bearings. The finger 26 may be and preferably is removable. The upper disk 21 is provided with an opening 28 adapted to register with a similar opening 29 in the body of the casting 20 when the post is turned to one position and the front runner is arranged in a plane directly 60 centrally of the rear runners. On the post there is supported by a flexible element 31 a 65 pin 32, and this pin is designed to be passed

through the registering openings in the disk and casting for locking the post from turning, and consequently locking the front or steering runner from likewise turning. The front runner is locked to the sled body when 70 the device is designed to be propelled by another sled or other vehicle, and to accomplish this I provide the front of the body 1 with an opening 33 through which the end of a tow rope may be passed and connected. 75

Secured on the under face of the body, directly to the rear of the under casting there is a transversely arranged rod 34. This rod, in a line with the sides of the body is bent downwardly, as at 35 and from thence outwardly, as at 36. The outturned portions 36 have their ends bent upwardly, as at 37. The portions 36 provide rests for the feet of the user of the sled.

The bearings through which the post 85 passes arrange the said post at an inward inclination so that the hand wheel thereon may be conveniently gripped by the operator.

It is thought that the foregoing description, when taken in connection with the drawings will fully set forth the construction and advantages of the improvement, but it is to be understood that I do not desire to be limited to the precise structural details herein set forth as I hold myself entitled to such changes therefrom as fall within the scope of my claims without departing from the spirit thereof.

It is, of course, obvious that in lieu of the hand wheel a laterally extending rod 100 may be passed through the post, and also that the post may be constructed of either wood or metal.

Having described the invention, I claim:

1. A sled comprising a body board, a frame formed of metal straps arranged rightangularly with respect to each other secured to the board and having downwardly directed angle ends, spaced connected runners to which the ends of the frame are secured, the ends of one of the frame members being continued and connected approximately centrally to the body, a runner normally arranged on a line running centrally between the first mentioned runners and forward thereof, said forward runner having a curved surface engaging edge, cross sectionally V-shaped metal shoes on all of the runners, a post removably secured to the forward runner passing through bearings in the body board, said bearings each comprising castings having oppositely beveled body portions, disks in the castings having lugs to which the post is secured and whereby the post is arranged at an angle 115 with respect to the body board, and an operating wheel for the post.

2. A sled comprising a body board, a frame formed of metal straps arranged rightangularly with respect to each other 120

secured to the board and having downward, 5 ly directed angle ends, spaced connected runners to which the ends of the frame are secured, the ends of one of the frame members being continued and connected approximately centrally to the body, a forward runner normally disposed centrally between the rear runners having a curved surface engaging edge, cross sectionally V-shaped metal shoes on all of the runners, 10 a post removably secured to the forward runner passing through bearings in the body board, said bearings each comprising castings having oppositely beveled body portions, 15 disks in the castings having lugs to which the post is secured and whereby the post is arranged at an angle with respect to the body board, anti-frictional means between the bearing elements, foot rests on the 20 body board, and a steering wheel on the post.

3. A sled comprising a body board, a frame formed of metal straps arranged rightangularly with respect to each other 25 secured to the board and having downward-

ly directed angle ends, spaced connected runners to which the ends of the frame are secured, the ends of one of the frame members being continued and connected approximately centrally to the body, a forward runner normally disposed centrally between the rear runners having a curved surface engaging edge, cross sectionally V-shaped metal shoes on all of the runners, a post removably secured to the forward runner 30 passing through bearings in the body board, said bearings each comprising castings having oppositely beveled body portions, disks in the castings having lugs to which the post is secured and whereby the post is arranged 35 at an angle with respect to the body board, means limiting the turning of the outer bearing elements, means for locking the inner and outer elements from turning one on the other, foot rests extending laterally 40 from the body board, and an operating wheel for the post.

In testimony whereof I affix my signature.

HARRY HEFFNER.
